Primary Examiner — Kevin Rudzinski(74) *Attorney, Agent, or Firm* — Muetting, Raasch & Gebhardt, P.A.(57) **CLAIM**

The ornamental design for a light shield for a concentrating photovoltaic system module, as shown and described.

DESCRIPTION

FIG. 1 is a top perspective view of a light shield for a concentrating photovoltaic system module;

FIG. 2 is a top plan view of the light shield of FIG. 1;

FIG. 3 is a bottom plan view of the light shield of FIG. 1;

FIG. 4 is a left side elevation view of the light shield of FIG. 1;

FIG. 5 is a right side elevation view of the light shield of FIG. 1;

FIG. 6 is a front side elevation view of the light shield of FIG. 1; and,

FIG. 7 is a rear side elevation view of the light shield of FIG. 1.
